UNITED STATES PATENT OFFICE.

CHARLES WORTH TURNER, OF NEW YORK, N. Y.

BURNER.

Application filed July 25, 1923, Serial No. 653,723. Renewed August 22, 1925.

This invention relates to burners and particularly to burners where an intense heat is provided and has for an object to provide a construction which is simple but which will project a comparatively intense flame either a short distance or a long distance, according to the position of the regulator of the burner.

Another object of the invention is to provide a burner using hydrocarbon oil and water vaporized and mixed in such a manner as to be combustible.

A still further object of the invention is to provide a burner in which a combustible mixture of water and oil is produced in a sufficient quantity to maintain the burner in proper condition for continuous generation and at the same time provide a flame for auxiliary heating.

20 In the accompanying drawing—

The figure is a perspective view of a burner, disclosing an embodiment of the invention.

Referring to the accompanying drawing by numerals, 1 indicates a supply tank containing water while 2 and 3 indicate supply tanks containing hydrocarbon oil. The tank 1 may be supplied with water from any suitable source and the water is preferably maintained under considerable pressure, as for instance, one hundred pounds to the square inch though it may be more or somewhat less if desired, according to the heat desired and the length of the flame. The oil tanks 2 and 3 are designed to supply oil to the pipe line 4 but usually only one tank is operated at a time and the respective valves 5 and 6 are, therefore, turned on and off as desired. These tanks are maintained under a pressure substantially equal to the pressure in tank 1, which pressure may be maintained by forcing water in the bottom of the tanks or in any other desired manner.

The tank 1 is supplied with water through a pipe 7 normally closed by the valve 8 while the tanks 2 and 3 are supplied with oil through the pipes 9 and 10 normally closed by the valves 11 and 12. These pipes are connected up to discharge pipes 13 and 14 and also to feed pipes 15 and 16. For instance, if the tank 3 should become empty, valve 5 is opened and valve 6 closed whereby oil is continually fed to the pipe 4. When this is done, valve 11 is opened whereby water may pass upwardly from pipe 15, through valve 19 and through valve 11 into

the tank 2 in order to maintain the pressure therein. When this is taking place the valves 17 and 18 are closed. In addition, the valve 12 is opened while the valves 21 and 22 are closed. The valve 20 is opened and the water in the tank 3 is allowed to flow out through the pipe 14 to a suitable discharge point. It will be understood that pipe 7 is connected to a suitable water supply maintained at the desired pressure while pipe 15 is connected to a suitable water supply to maintain the desired pressure in the tanks 2 and 3. After the water has all been discharged from the tank 3, valve 20 is closed and valve 22 opened, valve 18 being already closed. Oil is forced through the feed pipe 16, pipe 10 into tank 3 until it is filled whereupon valve 22 is closed and valve 21 opened. This will allow the water pressure in the feed pipe 15 to act on the tank 3 whereby it is in condition to be turned onto the pipe 4 whenever desired.

The tanks 2 and 3 are provided with valves at the upper part which may be opened whenever these valves are being drained of water. It will be noted that the construction provided is such that water under pressure may be used to maintain the pressure in tanks 2 and 3 but if preferred, oil could be continually supplied to these tanks under pressure or pressure could be provided by the use of compressed air. The desirable feature is to provide oil under continuous pressure for the pipe 4, which pressure is substantially equal to the pressure in tank 1. The pipe 4 extends to pipe 23 into which it merges and also into which it discharges oil, said pipe 23 being connected to the heating cylinder 24 near the bottom in any desired manner. The pipe 23 is provided with an extension 23' which merges into a pipe 25, said pipe 25 being connected to the tank 1 so as to be provided with water under pressure. Suitable hand operated valves 26 and 27 are provided in pipe 25 near each end and between these valves there is arranged a check valve 28 which will allow the water to pass from the pipe 25 to pipe 23' but will not allow any reverse movement. 105 A draining pipe 29 is also connected with pipe 25, said draining pipe being provided with a valve 30.

The proportion of oil and water may be varied according to circumstances, from equal parts oil and water to one part oil and eight parts water. Desirable results

have been secured by the proportion of five parts water and one part hydrocarbon oil, as for instance, crude oil. This mixture of water and oil is discharged at a desired pressure, as for instance, one hundred pounds to the square inch into the lower part of the cylinder 24, which cylinder is several times as long as its diameter. This cylinder is hollow and free of any obstructions interiorly. The cylinder 24 is maintained hot by the flame 31 and in addition the other cylinders 32, 33 and 34 are also maintained hot, the degree of temperature varying with the volume of flame desired and also somewhat varying by reason of the distance with which it is projected. For instance, where the pressure is one hundred pounds to the square inch in tanks 1, 2 and 3, the temperature in cylinder 24 is on an average about 500° F. As the oil and water is discharged at considerable pressure into the tank, it circulates round and round through the tank and becomes a more or less gaseous vapor by reason of this mixture and heat. This vapor or gas eventually passes out of pipe 35 connected to the upper end of the cylinder 24 preferably centrally thereof. The pipe 35 is connected at 36 to the lower end of cylinder 32 and discharges the gas from the upper end of cylinder 24 into the lower end of cylinder 32, which latter cylinder is maintained at a higher temperature, as for instance, 1000° F. This additional heat and movement of the gas as it circulates in the hollow cylinder 32 improves the condition of the gas and finally discharges the same through the pipe 37, which is preferably connected centrally of the upper end of cylinder 32. The pipe 37 leads the gas into the lower end of the cylinder 33, which latter cylinder is hotter than cylinder 32, as for instance, 1500° F. Gas after passing through this cylinder is naturally heated and becomes more nearly fixed gas. The gas finally is led out through the pipe 38 from the top of cylinder 33 to the bottom of cylinder 34. The cylinder 34 is usually much higher than cylinder 33, as for instance, 2000° F. As the gas leaves the cylinder 34 through pipe 39, it is almost a fixed gas and the water is thoroughly mixed or combined with the oil so that as the gas is led to the nozzle 40 it discharges from said nozzle into the tubular member 41 at a comparatively high pressure and very hot, approximately 200° F. The tubular member 41 is spaced from the tip 40 so that air may be drawn in with the gas and a Bunsen burner effect secured at this point. The air and gas mixes in the tube 41 and is ignited as it leaves this tube or a short distance thereabove whereby the flame 31 is projected in the space between the four cylinders and, consequently, heats these cylinders.

This flame not only heats these cylinders but projects a considerable pressure therebeyond for heating other objects. The flame may be projected a few feet or a large number of feet according to the pressure in the respective tanks 1, 2 and 3.

The size and shape of the tip 40 and the tube 41 also controls to a limited extent the distance which the flame may be drawn. Where the device is used to heat a large flat surface, the cylinders are preferably separated somewhat and a large flame produced at a comparatively reduced velocity whereas if the burner is to be used for heating, as for instance, steam boilers in ships, the flame is elongated and projected twenty or thirty feet or some other distance, according to the length of the burner.

During the formation of the combustible gas or mixture projected through the jet 40, there will be a certain amount of deposit of asphaltum or other heavy carbonaceous material, which deposits will be in liquid form and which may be drawn off from time to time through the respective pipes 42, 43, 44 and 45, said pipes discharging into the drain pipes 46 and 47, which drain pipes discharge into the pipe 48 leading to a suitable container or suitable place for discharge. Each of the pipes 42 to 45 inclusive, is provided with a valve so that the deposits cannot be moved out of the cylinders until these valves manually open and also so that the desired pressure will be maintained in the various cylinders. It will also be noted that the oil supply pipe 4 is provided with a hand actuated valve 49 and a check valve 50 which allows the oil to pass into the pipe 23 but prevents any return. A drain pipe 51 is also connected to pipe 4, said pipe being provided with a suitable valve 52. Preferably a gage is provided for the water tank 1, for the pipe 4 and for the jet 40 as the pressure in these members must be maintained at a given level in order to secure a certain desired result. It is evident that gages may be supplied at other points without departing from the spirit of the invention. It will also be noted that the cylinders 24, 32, 33 and 34 are held grouped together by a suitable band 53, which band is supported by suitable supporting legs or standards 54. It will, however, be evident that other kinds might be provided for holding these cylinders in their grouped formation and for assisting in supporting the same.

What I claim is:—

1. A burner, comprising a plurality of hollow gas producing units arranged in a circular group, the units of the group being so positioned as to present a central passageway in the group, means for forcing water and hydrocarbon oil into one of said units simultaneously, means for maintaining said

units heated, said means acting to produce a flame for not only heating the units but heating outside elements, said flame passing through said passage-way in said group, 5 and a plurality of means for leading the gasified oil and water from one unit to the other in series whereby its temperature is successively raised as it passes from one unit to the other and before it is discharged 10 as a combustible mixture, said mixture being discharged into the means for producing said flame.

2. A burner, comprising means for mixing a combustible mixture with air, means 15 for generating a gaseous mixture from water and hydrocarbon oil and discharging the same into the first mentioned means, said last mentioned means including a plurality of hollow members heated by the 20 flame from the first mentioned means, and a pipe leading from one hollow member to the other, said pipes being arranged so that the hollow member originally receiving the water and hydrocarbon oil will have its 25 pipe extend from the top to the bottom of the next hollow member and the next hollow member will have its pipe extending to the bottom of the next and so on for the entire group of hollow members in order that the 30 gaseous mixture may be successively heated and the heavier hydrocarbons split or cracked.

3. A burner, comprising a group of cylinders arranged in the same horizontal

plane, means for connecting the top of the 35 first cylinder to the bottom of the second, means for connecting the top of the second cylinder to the bottom of the third and so on to the last cylinder, means, for directing hydrocarbon and water into the bottom 40 of the first cylinder, a nozzle arranged opposite the center of said group of cylinders and positioned to discharge through the center of said cylinders, means for directing combustible mixture from the top of the last 45 mentioned cylinders to said nozzle, and means co-acting with the nozzle for mixing the combustible mixture with air whereby the discharge of the nozzle as it passes between said cylinders may be ignited for heating the cylinders and for projecting the 50 flame therebeyond.

4. In a burner, a plurality of not less than three hollow cylindrical gas generating elements, a pipe connecting the top of the 55 first element to the bottom of the second element and so on in tandem for the entire group, means for supplying water and hydrocarbon oil to the bottom of the first cylinder, means for providing a flame for 60 heating said elements and at the same time projecting the flame beyond the elements for heating other objects, and means for directing combustible mixture in the last of said generating elements to the means for projecting the flame. 65
